UNITED STATES PATENT OFFICE.

THOMAS W. MORGAN, OF WATERLOO, IOWA, ASSIGNOR TO WILBUR W. MARSH, OF WATERLOO, IOWA.

DESIGN FOR A CENTRIFUGAL CREAM-SEPARATOR.

No. 38,944.

Specification for Design.

Patented Dec. 10, 1907.

Application filed June 25, 1907. Serial No. 380,838. Term of patent 14 years.

To all whom it may concern:

Be it known that I, THOMAS W. MORGAN, a citizen of the United States, residing at Waterloo, in the county of Blackhawk and State of Iowa, have invented a new, original, and ornamental Design for the Frame of a Centrifugal Cream-Separator, of which the following is a specification, reference being had to the accompanying drawing, forming part thereof.

The figure is a perspective view of the frame of a centrifugal cream separator, showing my new design.

I claim:

The ornamental design for a frame for a centrifugal cream separator, as shown.

THOMAS W. MORGAN.
